UNITED STATES PATENT OFFICE.

FREDERICK HABERMAN, OF NEW YORK, N. Y.

SHEET-METAL VESSEL.

SPECIFICATION forming part of Letters Patent No. 390,591, dated October 2, 1888.

Application filed June 14, 1888. Serial No. 217,053. (No model.)

To all whom it may concern:

Be it known that I, FREDERICK HABERMAN, a citizen of the United States, residing at New York, in the county and State of New York, have invented new and useful Improvements in Sheet-Metal Vessels, of which the following is a specification.

This invention relates to an improvement in sheet-metal vessels, as set forth in the following specification and claims, and illustrated in the accompanying drawings, in which—

Figure 1 is a side elevation of a vessel. Fig. 2 is a section along the line *x x*, Fig. 1. Fig. 3 is a detail view of part of a wall of a vessel. Fig. 4 is a section along the line *y y*, Fig. 3. Fig. 5 is a rear view of a spout. Fig. 6 is a section along the line *z z*, Fig. 5. Fig. 7 is a detail view of part of a spout.

Similar letters indicate corresponding parts. In the drawings, the letter A indicates a vessel-body, and B C are handles. To said vessel, and communicating with the interior thereof, is secured a spout, F. Said spout is shown secured by means of grooves D, Fig. 4, and tongues E, Fig. 6. Said spout is shown as having a brace, G, the walls of the brace being strengthened or prevented from bending or bulging by beads H, formed in said brace-walls. The discharge K of the spout is located above the upper portion or brim of the vessel-body, so that the vessel can be made brimful of liquid without the liquid flowing out of the spout F until the vessel is properly tilted.

The spout may be provided with a suitable attachment—such as a sprayer, L. The upper portions of the brace-walls are shown held apart by a roof or top brace, I, and the space or chamber between the brace-walls G forms a continuation of the space or chamber of the vessel A, thus adding to the capacity of the vessel.

The spout is composed of two sections of metal, each of which sections is formed integral with one longitudinal half of the spout, 45 one of the brace-walls G, and one of the laterally-projecting tongues E. The metallic sections so formed are united at the top of the brace-walls and along the front of the spout by the seams M, so that the walls are parallel and separated. The beads H extend in a triangular path on the brace-walls, so as to strengthen the latter in three different directions, thereby securing the best results.

What I claim as new, and desire to secure by Letters Patent, is—

1. A sheet-metal vessel having a spout and brace-walls composed of two metal sections, each formed integral with one longitudinal half of the spout, one of the brace-walls G, and 60 one of the laterally-projecting tongues E at the inner edge of the latter, said sections united along the front of the spout and at the top of the brace-walls by the seams M M, and the brace-walls separated to form a chamber which increases the capacity of the spout, substantially as described.

2. The combination, with the vessel A, having the grooves D, of a spout composed of two metal sections, each formed integral with a beaded brace-wall, G, and a lateral tongue, E, at the inner edge of the latter, said sections united along the front of the spout and along the tops of the brace-walls by the seams M M, and said brace-walls separated to form a chamber which increases the capacity of the spout, substantially as described.

In testimony whereof I have hereunto set my hand and seal in the presence of two subscribing witnesses.

F. HABERMAN. [L. S.]
